UNITED STATES PATENT OFFICE.

JOSEPH E. FORSYTH, OF CHICAGO, ILLINOIS, ASSIGNOR TO MARTIN K. NORTHAM, OF CHICAGO, ILLINOIS.

DRAFT GEAR.

Application filed November 23, 1925. Serial No. 70,802.

This invention relates particularly to draft-gears of the type utilizing both spring pressure and friction in the buffing and pulling operations.

5 The primary object of the invention is to provide auxiliary means for increasing buffing resistance of standard draft-gear mechanism of any desired construction. The desired result is attained by employing in 10 combination with a draft-gear of any desired or usual construction an auxiliary spring buffer which is disposed in front of the end of the substructure of the car-body, this auxiliary device co-acting ordinarily 15 with the horn of the standard draw-bar.

The invention is illustrated in its preferred embodiment in the accompanying drawings, in which—

Fig. 1 represents a vertical sectional view 20 of the improved draft-gear applied to the substructure of a car which is shown brokenly; Fig. 2, a broken transverse sectional view taken as indicated at line 2 of Fig. 1; and Fig. 3, a broken plan view of the apparatus with the upper plate spanning the longitudinal members of the substructure removed.

In the construction illustrated, A, A' designate longitudinal frame members constituting a part of the substructure of a car; 30 A², an end cross-member which corresponds with or constitutes the end of the substructure; A³, transverse bars connecting the lower edges of the longitudinal members A and A'; A⁴, a plate connecting the upper edges of said longitudinal members; A⁵, a pair of front stops for the draft-gear secured to the inner surfaces of the longitudinal members A and A'; A⁶, a pair of rear stops for the draft-gear secured to the members A and A'; B, a draft-gear of any desired construction interposed between the front pair of stops A⁵ and the rear pair of stops A⁶, said draft-gear having connected 40 therewith the usual draw-bar B', the head of which is provided at its upper portion with a shoulder, or horn, B²; and C, the improved auxiliary buffing device mounted on the substructure in front of the end cross-beam A² and co-acting with the head portion of the draw-bar.

The draft-gear B may be of any desired construction adapted to be introduced within the space provided therefor between the intermediate longitudinal members A and

A' of the substructure of the car-body. In the illustration given, the draft-gear B comprises a pair of spring-holders 1 and 2 containing springs 1^a and 2^a and equipped with spring-followers 1^b and 2^b. In accordance with a well-known construction, a rock-member 3 is introduced between the spring-followers 1^b and 2^b. The parts just described are contained within a yoke 4 whose front end is connected by a key 5 with the shank of the draw-bar B' by lost motion connection, in the usual manner.

The auxiliary buffing device C, in the form illustrated, comprises a spring-casing 6 disposed in front of the end cross-beam A² and secured to the depending flange thereof by rivets 6^a; a vertically disposed coil-spring 7 mounted in the upper portion of the casing 6; a vertically movable spring-follower 8 disposed beneath the spring 7, said follower being provided with wedge-surfaces 8^a; and a horizontal reciprocable plunger 9 disposed below the follower 8 and provided with wedge-surfaces 9^a which coact with the surfaces 8^a.

The casing 6 has a bottom wall 10, a rear wall 10^a, a top wall 10^b, and a front wall 10^c. The front wall is cut away at its lower portion, as indicated at 10^d. The spring 7 and the wedge-members may be introduced through the opening thus provided. The parts are held in place by a metal strap 11 which engages a lug 9^b with which the wedge-member, or plunger, 9 is equipped at its upper side. The strap 11 is secured to the casing 6 by means of bolts 11^a.

The draw-bar B' works freely through a yoke, or support, 12, in the usual manner. The auxiliary buffing device C is superposed above the draw-bar, and the wedge-member, or plunger, 9, has a projecting portion 9^c which is adapted to be engaged by the horn B² of the coupler during the buffing operation.

In the operation of the improved draft-gear, the standard, or ordinary, draft-gear B with which the car is equipped operates in the usual manner. That is, when a pull is exerted through the medium of the draw-bar, the strain is taken by the springs and friction devices of the draft-gear B; and when a buffing action occurs, the push is yieldingly opposed by the springs and friction devices of the draft-gear B. The resistance offered by the draft-gear B in the

buffing operation is supplemented by the action of the auxiliary buffing device C. That is, before the draw-bar reaches the rearward limit of its movement, the horn B² engages 5 the projection 9° of the lower wedge-member 9 and forces the lower wedge-member rearwardly, thereby causing the upper wedge-member 8 to move upwardly and compress the spring 7. The device C is designed 10 to prevent the horn B² from striking a dead stop in the buffing operation. In practice, the standard draft-gear may withstand a compression of, say, three hundred thousand pounds or more; and the yielding resistance 15 may be increased perhaps one-third by means of the auxiliary buffing device C. It will be understood, of course, that in addition to the resistance offered by the spring 7, further resistance is offered by the friction between 20 the wedge-members 8 and 9, the friction between the wedge-member 9 and the bottom of the casing 6, and the friction between the wedge-member 8 and the rear wall of the casing 6.

25 It will be understood from the foregoing description that by means of the simple expedient described it is possible to enormously increase the buffing resistance of the draft-gear. Moreover, the improved auxiliary buffing device can be readily installed 30 on cars of standard construction.

The foregoing detailed description has been given for clearness of understanding only, and no unnecessary limitations should 35 be understood therefrom, but the appended claims should be construed as broadly as permissible, in view of the prior art.

What I regard as new, and desire to secure by Letters Patent, is:

1. The combination with the substructure 40 of a car-body and a draft-gear mounted in said substructure and equipped with a draw-bar projecting beyond the end of the substructure, the projecting end of said draw-bar having its upper side equipped with a 45 shoulder, of an auxiliary spring-housing mounted on said substructure and disposed above said draw-bar and having an opening at its lower front portion, a coil-spring in said housing having a vertical axis, said 50 spring being insertable through said opening, and co-acting wedge-members interposed between said spring and the bottom of said housing, one of said members having a portion 55 adapted to be engaged by said shoulder.

2. The combination with the substructure 60 of a car and a draft-gear mounted therein equipped with a draw-bar projecting beyond said substructure and having its projecting end-portion equipped on its upper surface 65 with a horn, of a spring-housing secured to said substructure and disposed above the draw-bar, said housing having its front wall provided with an opening, a coil-spring located in the upper portion of said housing, wedge-members interposed between said 70 spring and the bottom of said housing, the lower one of said wedge-members having a projection adapted to be engaged by said horn in the buffing operation, and means removably secured to said housing and partially projecting over said opening serving to retain said wedge-members in position.

JOSEPH E. FORSYTH.
